W. CLASEN

LIQUID FUEL BURNER

Filed Sept. 24, 1923

Fig. 1.

UNITED STATES PATENT OFFICE.

WILHELM CLASEN, OF BERLIN, GERMANY, ASSIGNOR TO RICHARD KAHN AKTIEN-
GESELLSCHAFT, OF BERLIN, GERMANY, A CORPORATION OF GERMANY.

LIQUID-FUEL BURNER.

Application filed September 24, 1923. Serial No. 664,572.

To all whom it may concern:

Be it known that I, WILHELM CLASEN, a citizen of the German Republic, and resident of Berlin, Germany, have invented 5 certain new and useful Improvements in Liquid-Fuel Burners, of which the following is a specification.

My invention relates to a method of and means for the working of combustion burners with previously heated air.

In the burners in general use the suction of air and the circulation of the fuel fumes is only obtained by the combustion energy of the fuel, as for example, gas, and the flame of these burners is, therefore, comparatively "feeble". This is especially so in that class of burners in which heated air is used, because the previous heating causes the air to expand and brings about 20 a diminution of the volume of air sucked in.

The manner in which the previously warmed air is conveyed to the fuel in these burners, is so inefficient that not only is 25 the desired aim not attained, but the contrary is brought into effect in so far as the vital strength of the fuel stream is too freely expanded on the sucking in of air. Owing to this, the flow of fuel loses its 30 velocity instead of being accelerated by the heated self-expanding air. This disadvantage is obviated by the method of the invention.

My invention essentially consists in the 35 fact that the air is conveyed to the burner so highly heated (at about 400° C. and more) that the action of the injection of the flowing fuel, and thereby the velocity of its stream is increased by the superheated air.

40 This method may be suitably carried out by producing a super-pressure of air in the injector-pipe by placing the inlet for the cold air lower than the inlet of the injector-pipe for fuel and heated air. Owing to this 45 difference in height, a particularly strong expansion of the upper air towards the injector is produced whereby the suction-power of fuel stream is increased and facilitated.

50 The increased flow of fuel available through this accelerates the velocity of combustion, so that the flame, without the need of any special mechanical contrivances, assumes the character of a blow-burner,

and consequently shows higher working efficiency. 55

The regulation of the volume of in-streaming air is, contrary to accepted rules, effected in this invention, after previous heating in the interior of the burner-head. The 60 methods to be used for this may be various.

The drawing shows two burners, Figs. 1 and 2, in vertical section as working examples to explain the method of my invention. 65

In the construction shown in Fig. 1, the injector pipe *b* is movably fixed by means of the ribs *f* in the open topped cup *c* into which nipple *d* of the fuel pipe *d'* is screwed. 70

The bore *b'* of the injector pipe *b* is upwardly tapered, while its exterior forms one of the walls of the circular canal for the air. The injector pipe *b* forms at the same time the bottom of the expansion 75 chamber *e* and carries the outer member *a* of the burner which is closed at the top and has the lateral burning apertures *g*.

The spreader *a'* of the outer member of the burner is not smooth at the bottom, but 80 is so formed that the gas mixture, streaming from the injector, is gradually directed to the apertures *g* of the burner. As an example, the spreader *a'* can, at its base, be shaped in the form of a parabola. 85

By means of the flame, the outer member *a* of the burner becomes strongly heated. As there is a comparatively large amount of metal in the vicinity of the flame, this heating is very lasting. The air entering 90 the circular chamber between the two members *a* and *c* becomes, therefore, at once very highly heated, and the velocity of its flow produced by the action of the injector, becomes efficiently accelerated. A particularly 95 favourable result is obtained when the member *a*—as is shown by the dotted lines of Fig. 1—reaches so far down that between its lower rim and the rim of the injector-pipe *b* the difference in height *y* is formed. 100 This difference in height, together with the heating of the fuel, produces an expansion which appears as a super-pressure of air and produces a hot intense blow flame.

In order to be able to use the burner for fuel of different quality, the injector pipe *b* is contrived to be easily exchangeable, so that for a rich fuel one with a small bore, 105

and a thereby enlarged air channel, and for a poorer mixture, one with a wider bore and a narrower air channel may be fitted.

In this way the regulation of the supply 5 of air from outside, which depends for its satisfactory working on the intelligence and goodwill of servants, is obviated.

Instead of making the injector pipe b to be easily exchangeable, it is possible, as 10 shown in Fig. 2, to retain the same injector pipe, and to obtain the regulation of the air supply by having in the member c a second cup shaped member c^1 . The member c is formed by the plate b^2 which covers it 15 as well as the part c^1 . The two members c , c^1 are furnished with slits or holes i , i^1 which cover each other in such a position as to allow of the passage of the greatest volume of air. By turning the member c 20 the air holes i , i^1 can be adjusted. After this is done, the outer member a is put on, and by this means the regulation of the air is removed from all outside influence. By means of a pin h which is screwed into the 25 outside member a and fits into a slot in the plate b^2 the regulation of the current of air can be effected, even during combustion.

As the handle or pin h is placed immediately below the flame, it can only be 30 moved intentionally, and not by accident.

I claim as my invention:

1. A burner, comprising in combination, 35 a fuel pipe nipple, a cup-shaped part surrounding the nipple, an injector tube projecting into said cup-shaped part, a second cup-shaped part closed at its upper side and arranged above the first cup-shaped part and said injector tube respectively, the second cup-shaped part being arranged to form 40 a mixing chamber into which the injector tube directly discharges and provided with lateral burner openings in the side wall, and air ducts between said cup-shaped parts, leading the outer air to the intake end of 45 the injector tube.

2. A burner, comprising in combination, 50 a fuel pipe nipple, a cup-shaped part surrounding the nipple, an injector tube projecting into said cup-shaped part, and carried by the latter, a second cup-shaped part closed at its upper side and detachably arranged on the first cup-shaped part and said injector tube respectively, the second cup-shaped part being arranged to form a 55 mixing chamber into which the injector tube directly discharges and having its side wall projecting over the first cup-shaped part and provided with lateral burner open-

ings, and air ducts between said cup-shaped parts, leading from the outer air to the 60 intake end of the injector tube.

3. A burner, comprising in combination, 65 a fuel pipe nipple, a cup-shaped part surrounding the nipple, an injector tube projecting into said cup-shaped part, and carried by the latter, a second cup-shaped part closed at its upper side and detachably arranged on the first cup-shaped part and said injector tube respectively, the second cup-shaped part being arranged to form a 70 mixing chamber into which the injector tube directly discharges and having its side wall extending downwardly below the entrance aperture of said injector tube and surrounding the first cup-shaped part to form an 75 air channel between said cup-shaped parts, said side wall also having lateral burner openings near its upper edge.

4. A burner, comprising in combination, 80 a fuel pipe nipple, a cup-shaped part surrounding the nipple, an injector tube projecting into said cup-shaped part, a second cup-shaped part closed at its upper side and arranged above the first cup-shaped part and said injector tube respectively, the second cup-shaped part being arranged to form a 85 mixing chamber into which the injector tube directly discharges and provided with lateral burner openings in the side wall, air ducts between said cup-shaped 90 parts leading from the outer air to the intake end of the injector tube, and means for regulating the inflow of air arranged on the first cup-shaped part.

5. A burner, comprising in combination, 95 a fuel pipe nipple, a cup-shaped part surrounding the nipple, an injector tube projecting into said cup-shaped part, a second cup-shaped part closed at its upper side and arranged above the first cup-shaped 100 part and said injector tube respectively, the second cup-shaped part being arranged to form a mixing chamber into which the injector tube directly discharges and provided with lateral burner openings in its side wall, 105 air ducts between said cup-shaped parts, air entrance openings in the first cup-shaped part, and means turnable in the latter for regulating the flow of air.

In testimony whereof I affix my signature in presence of two witnesses.

WILHELM CLASEN.
